N° 977.

*David Hathaway's "Consul" Design for a Stove Door;
Assigned to Fuller, Warren & Morrison, Troy, N.Y.*

Patented Jan'y 12. 1858.

Des. 977

David Hathaway, of Troy, N.Y.
Assignor to
Fuller, Warren, and Morrison of same place.
Letters Patent No. 977, dated Jan 12th 1858.

The schedule referred to in these Letters Patent and making part of the same.

To all whom it may concern:

Be it known that I, David Hathaway of the city of Troy, in the County of Rensselaer, and State of New York, have invented or produced a new and original Design for a Door of a cooking Stove: - and I do hereby declare that the following is a full and exact description of the same, reference being had to the annexed photographic drawing making a part of this Specification.

My ornamental design for a door of a stove consists of the obliquely furrowed, oblong, hexagonal, sunk panels, a, and the square, check-work, sunk panels, b, shaped and arranged together upon the plate as shown in the annexed photograph.

What I claim as my invention or production & desire to secure by Letters Patent is, the design for a door of a stove as herein described & M. 1 and shown in the annexed photographic drawing. -

Witnesses: -

Marcus Ball.

Alphonse Picard.

David Hathaway.
